UNITED STATES PATENT OFFICE.

ISAAC H. MILLIKEN, OF ASPINWALL, AND WILLIAM J. REGAN, OF PITTSBURGH, PENNSYLVANIA, ASSIGNEES TO THE MC CONWAY & TORLEY COMPANY, OF PITTSBURGH, PENNSYLVANIA, A CORPORATION OF PENNSYLVANIA.

UNCOUPLING MECHANISM.

1,417,548.

Specification of Letters Patent. Patented May 30, 1922.

Application filed October 6, 1921. Serial No. 505,695.

To all whom it may concern:

Be it known that we, ISAAC H. MILLIKEN and WILLIAM J. REGAN, citizens of the United States, residing, respectively, at Aspinwall, in the county of Allegheny and State of Pennsylvania, and Pittsburgh, in the county of Allegheny and State of Pennsylvania, have invented certain new and useful Improvements in Uncoupling Mechanism; and we do hereby declare the following to be a full, clear and exact description of the invention, such as will enable others skilled in the art to which it appertains to make and use the same.

Our invention relates to uncoupling mechanism for operating the lock of a car coupler. While it is especially designed to afford uncoupling means well suited for application to the Master Car Builders' D-type coupler of the form employing a bottom operated lock, the invention may be embodied in uncoupling mechanism for use with other forms of couplers as well.

The principal object of the invention is to provide an efficient and easily operated uncoupling mechanism constructed of a few simple parts which are combined in a compact form.

Generally stated, the primary feature of the invention consists in actuating the lock of the coupler by means of a rotatable member operatively connected to said lock and slidably supported upon and adapted to be actuated by a member affording a support for an uncoupling lever, the said uncoupling lever supporting member being pivotally connected to a bail which is swingingly sustained by the coupler carrier iron and the said point of support for the uncoupling lever being below the point of pivotal connection of the said actuating member and bail.

A further feature of the invention consists in moving the coupler lock to unlocked position by means of a rotatable member which is caused to perform an unlocking rotation by means of an actuating device adapted to be rotated by an uncoupling lever which is pivotally connected to a bail adapted to swing lengthwise of the car, the actuating device being provided with a recess which is open laterally below the axis of pivotal connection of the said actuating device and bail to permit the entry of the uncoupling lever.

Another feature of the invention consists in moving the coupler lock to unlocked position by the employment of a vertically rotatable member adapted to be actuated by a device provided with a plurality of trunnions journaled in corresponding hooks formed at the lower end of a bail that is mounted on the car so as to be capable of swinging lengthwise with respect thereto.

There are further features of the invention residing in particular combinations of parts and elemental details of construction, all as will hereinafter appear.

In the drawings illustrating the invention, the scope whereof is pointed out in the claims:

Figure 1 is a view, partly in side elevation and partly in vertical section, of an uncoupling mechanism embodying the invention, the car coupler being of the well known Master Car Builders' standard D-type.

Figure 2 is a view, partly in side elevation and partly in vertical section, of a portion of the construction illustrated in Fig. 1, the parts being shown in the positions they occupy when the coupler lock has performed an extended unlocking movement, and a somewhat different form of coupler carrier iron device being illustrated.

Figure 3 is a detail view, partly in rear elevation and partly in section, of a portion of the mechanism, parts of the uncoupling levers being broken away.

Figure 4 is a detail view in side elevation of a portion of the mechanism, the forward end of the vertically rotatable uncoupling bar being broken away.

Figure 5 is a detail longitudinal section of a portion of the mechanism, a part of the vertically rotatable bar and the inner end of one of the uncoupling levers being shown in elevation.

Figure 6 is a detail view, partly in plan and partly in horizontal section, of the rear portion of the uncoupling mechanism, parts of the uncoupling levers and the forward end of the vertically rotatable bar being broken away.

Figure 7 is a detail sectional view on the line 7—7, Fig. 1.

The car coupler 1 illustrated in the drawings is of the well known Master Car Builders' D-type. The lower end of its lock 2 is movably connected to a link 3 which projects

downwardly through the coupler head and is pivotally connected to a swinging lift lever 4 that is itself pivotally mounted upon the under side of the head of the coupler. 5 The link 3 and pivoted lift lever 4 preferably correspond in form and function with the standard parts of the bottom lift devices employed in the D coupler.

If the coupler is to be capable of extended 10 lateral swinging movements its shank may be provided near the rear end thereof with a pivot pin opening 5 for receiving the tail pin (not shown) constituting the means for pivotally connecting the coupler to the draft 15 rigging in a well known manner.

The lift lever 4 is caused to perform an unlocking movement by the vertical rotation of a member 6 whose forward end is pivotally connected to the lift lever and whose 20 rear end is slidably supported upon an actuating member 7 which is pivotally mounted upon a bail 8 suspended from the coupler carrier iron in a manner to permit said bail to swing lengthwise of the car. The member 6 may conveniently be formed as a simple bar having a hooked forward end 9 adapted to pass through the usual eye or opening 10 at the inner end of the lift lever 4.

30 The preferred modes of supporting the swinging bail 8 from two well known forms of coupler carrier iron devices are illustrated in the drawings. The carrier iron device shown in Fig. 1, and generally designated by the reference numeral 11, will be recognized as one now in use upon Pullman cars; while the carrier iron 12 shown in Fig. 2 is of another well known form. It is to be understood, however, that the invention is not limited to any particular form of coupler carrier iron. The bail 8 may be detachably supported from the carrier iron 11 by securing to said carrier iron a casting having a hook 13 adapted to receive the upper end of said bail and through which the latter may be threaded. In case the carrier iron 12 is employed the bail 8 may be supported therefrom by providing said carrier with a bracket formed at its lower end with 45 an eye 14 through which the bail may be passed.

To form the pivotal connection between the bail 8 and the actuating member 7 the said bail may conveniently be provided at 55 its lower end with spaced hooks 15 forming journal bearings for corresponding trunnions 16 projecting laterally from opposite sides of the actuating member 7. The trunnions 16, which may be flattened on their upper sides so as to have a segmental form contributing to the compactness of the mechanism, are preferably provided at their outer ends with marginal flanges 17 which, by overlapping the outer sides of the respective hooks 15 of the bail, serve to prevent

said bail 8 from spreading when the device is in service.

The actuating member 7 has a recess 18 for receiving the upwardly projecting inner ends 19 of the rotatable uncoupling levers 20 that extend toward the sides of the car in the usual manner, the said recess 18 being open laterally at 21 below the trunnions 16 to permit the uncoupling levers to be entered in and supported on the actuating 75 member 7 below the axis of its pivotal connection with the bail 8. As shown in the drawings, the recess 18 and the lateral openings 21 are wider at the bottom than at the top. This permits either uncoupling lever 20 to be used for unlocking the coupler independently of the other lever. The uncoupling levers are preferably of the well known form illustrated in the I. H. Milliken Patent No. 1,184,116, dated May 23, 1916. 80

To assist in stabilizing the actuating member 7 against the possibility of an accidental uncoupling movement due to the dragging of the bar 6 thereon as the coupler moves longitudinally, the member 7 is preferably 90 formed with portions 22 and 23 which normally engage the under side of the rotatable bar 6 in advance of and to the rear, respectively, of the axis of pivotal connection of said actuating member to its supporting bail 95 8. To the rear of said pivotal axis and above the trunnions 16 by which this pivotal connection is effected, the actuating member 7 is provided with an opening 24 through which the rear end of the member 6 extends. 100 The upper wall or boundary 25 of the opening 24 is adapted to come into engagement with the upper side of the rotatable bar 6 when the latter is actuated to cause an unlocking movement of the coupler lock 2. 105

When either of the uncoupling levers 20 is operated its bent inner end 19 presses against the forward wall 26 of the swinging supported actuating member 7 and causes the latter to execute an upward pivotal movement on the supporting bail 8. This movement of the member 7 causes the portions 22 and 25 thereof to press respectively upon opposite sides of the vertically rotatable bar 6 in advance and to the rear of the axis of the trunnions 16, thereby compelling the member 6 to perform an unlocking rotation which is communicated to the coupler lock 2 through the lift lever 4 and the link 3. During the unlocking movement of the rotatable bar 6 and its actuating member 7 the bail 8 swings lengthwise of the car as may be required to enable the hooked end 9 of the bar 6 readily to follow the path of travel of the eye 10 at the inner end of the 115 lock lift lever 4.

In the embodiment of the invention illustrated in the drawings the several parts of the uncoupling mechanism are detachably interlocked so that their accidental disas- 130

sociation when the device is in service is prevented.

We claim:

1. In an uncoupling mechanism, the combination with a car coupler, its lock and carrier iron, of means for moving said lock to unlocked position, said means involving a rotatable member operatively connected to said lock, a bail swingingly supported by said carrier iron, means pivotally connected to said bail adapted to actuate said rotatable member, and an uncoupling lever supported on said actuating means at a point below the point of pivotal support of said actuating means.
2. In an uncoupling mechanism, the combination with a car coupler and its lock, of means for moving said lock to unlocked position, said means involving a rotatable member operatively connected to said lock, a swinging bail, means pivotally connected to said bail for actuating said rotatable member, and an uncoupling lever for operating said actuating means, said actuating means being provided with a recess which is open laterally below the axis of pivotal connection of said actuating means and bail to permit the entry of said uncoupling lever.
3. In an uncoupling mechanism, the combination with a car coupler and its lock, of means for moving said lock to unlocked position, said means involving a vertically rotatable member operatively connected to said lock and extending rearwardly therefrom, a swinging bail, a member pivotally connected to said bail for actuating said rotatable member, and an uncoupling lever for operating said actuating member, the said pivotal connection of said bail and actuating member involving a plurality of trunnions.
4. In an uncoupling mechanism, the combination with a car coupler, its lock and carrier iron, of means for moving said lock to unlocked position, said means involving a vertically rotatable member operatively connected to said lock, a bail supported from said carrier iron and adapted to swing lengthwise of the car, means pivotally connected to said bail for actuating said rotatable member, and an uncoupling lever for causing an unlocked movement of said actuating means, said pivotal connection of said bail and actuating means being effected by a plurality of hooks and corresponding trunnions.
5. In an uncoupling mechanism, the combination with a car coupler and its lock, of means for moving said lock to unlocked position, said means involving a vertically rotatable member operatively connected to said lock and extending rearwardly therefrom, a bail adapted to swing lengthwise of the car and provided with a plurality of spaced hooks, and a member slidably engaging and adapted to actuate said rotatable member and provided with a plurality of laterally projecting trunnions adapted to cooperate with said hooks to form a pivotal connection with said bail.
6. In an uncoupling mechanism, the combination with a car coupler and its lock, of means for moving said lock to unlocked position, said means involving a rotatable member operatively connected to said lock, a bail adapted to swing lengthwise of the car and provided at its lower end with a plurality of hooks forming trunnion bearings, and a member adapted to actuate said rotatable member, said actuating member being provided with a plurality of flanged trunnions which are journaled in said hooks.
7. In an uncoupling mechanism, the combination with a car coupler and its lock, of means for moving said lock to unlocked position, said means involving a rotatable member operatively connected to said lock and extending rearwardly therefrom, a member adapted to actuate said rotatable member, means pivotally connected to said actuating member and adapted to move lengthwise of the car for supporting said actuating member, and means for operating said actuating member, said actuating member being provided with portions which are adapted to engage slidably the under side of said rotatable member in advance and to the rear of the axis of pivotal connection of said actuating member to its supporting means.
8. In an uncoupling mechanism, the combination with a car coupler and its lock, of means for moving said lock to unlocked position, said means involving a rotatable member operatively connected to said lock and extending rearwardly therefrom, means for actuating said rotatable member, means adapted to swing lengthwise of the car pivotally supporting said actuating means, and means for operating said actuating means, said rotatable member being adapted to slide lengthwise of the car with respect to said actuating means, and said actuating means being provided with trunnions journaled on said supporting means.
9. In an uncoupling mechanism, the combination with a car coupler and its lock, of means for moving said lock to unlocked position, said means involving a rotatable member operatively connected to said lock and extending rearwardly therefrom, a member slidably supporting the rear end of said rotatable member and adapted to actuate said rotatable member, and means adapted to swing lengthwise of the car for supporting said actuating member, said actuating member being provided with a plurality of trunnions journaled in said last named means, and said actuating member also being provided above said trunnions with an aperture through which the rear end of said rotatable member extends.

10. In an uncoupling mechanism, the combination with a car coupler and its lock, of means for moving said lock to unlocked position, said means involving a rotatable member operatively connected to said lock and extending rearwardly therefrom, a member adapted to actuate said rotatable member to effect a lock operating movement thereof, means adapted to swing lengthwise of the car for supporting said actuating member, and an uncoupling lever for operating said actuating member, said actuating member being provided with trunnions journaled on said swinging means and being formed with a recess which is open laterally below said trunnions to permit the entry of said uncoupling lever.

11. In an uncoupling mechanism, the combination with a car coupler and its lock, 20 of means for moving said lock to unlocked position, said means involving a rotatable member operatively connected to said lock and extending rearwardly therefrom, a member for actuating said rotatable member, supporting means for said actuating member adapted to swing lengthwise of the car and pivotally connected to said actuating member, and an uncoupling lever for operating said actuating member, said rotatable member being slidably lengthwise of the car with respect to said actuating member, and said actuating member being provided with trunnions journaled on said

swinging supporting means and having an opening above said trunnions through 35 which said rotatable member extends and also having a recess which opens laterally below said trunnions to permit the entry of said uncoupling lever.

12. In an uncoupling mechanism, the combination with a car coupler and its lock, of means for moving said lock to unlocked position, said means involving a rotatable member operatively connected to said lock and extending rearwardly therefrom; an 45 actuating member slidably supporting said rotatable member rearwardly of said lock and adapted to cause an unlocking rotation of said rotatable member, and supporting means for said actuating member adapted 50 to swing lengthwise of the car and pivotally connected to said actuating member, said actuating member being adapted to have supporting engagement with the under side of said rotatable member in advance and to 55 the rear of the axis of pivotal connection of said actuating member to said swinging supporting means, and said actuating member also being adapted to engage the upper side of said rotatable member to the rear of said 60 pivotal axis.

In testimony whereof we affix our signatures.

ISAAC H. MILLIKEN.
WILLIAM J. REGAN.
